UNITED STATES PATENT OFFICE.

JOSEPH LINDBURG, OF BROOKLYN, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed July 17, 1924. Serial No. 726,424.

This invention relates generally to sound-deadening casings for typewriting machines, and more particularly to an adjustable spring device co-operating with the cover thereof to automatically open the same when access is desired to the typewriter.

One feature of the invention is the provision of means for obtaining a minute adjustment of the spring tension of the device, so as to regulate the action thereof to obtain the necessary force for properly opening the cover, while at the same time providing a compact structure of sufficient mechanical strength to transmit the action of a heavy spring through the adjusting means and to the cover without danger of breaking or injuring the adjusting means.

Another feature is the provision of means for gradually arresting the movement of the cover when it is approaching the open position, thus eliminating any possibility of jar or vibration to the casing or the machine contained therein.

Other features and advantages will hereinafter appear.

In the accompanying drawings,

Figure 1 is a cross-section through the sound-deadening casing showing the cover in closed position.

Figure 2 is a somewhat reduced view similar to Figure 1, but showing the cover opened.

Figure 3 is a plan view of one end of the casing, the cover being broken away to show the cover-opening device.

Figure 4 is an enlarged vertical section on the line 4—4 of Figure 2.

The sound-deadening casing comprises two main parts, namely, a housing 10 and a cover 11, the cover being hinged at 12 to swing between the positions indicated by Figures 1 and 2. Both the housing 10 and the cover 11 may be formed from sheet material and lined on their inner walls with suitable sound-deadening material, such as that indicated at 13. The front wall 14 of the housing 10 is cut away at 15 to allow the keyboard extension of a typewriting machine (not shown) to protrude there-through the upper portion of the machine extending under the cover 11, as shown in dot-and-dash lines at 16. A window 17 in

the cover 11 permits the work being typed in the machine to be observed. Carriage-operating levers 18 extend through a slot 18' formed between the upper edge of the front wall 14 of the housing 10 and the forward edge 19 of the cover 11, the slot being practically closed by two resilient flexible cushions 20 and 21 carried respectively by the cover and housing.

For locking the cover in closed position, there is pivoted at 22 to one of the side walls of the cover a latch 23, which extends into the body of the housing 10 and is provided with a hooked end 24 which is spring pressed into engagement under a lip or detent 25 fastened to the interior of the housing. The latch 23 may be disengaged from the detent 25 by pressure upon a finger-piece 26. The cover 11 is caused to automatically open when the finger-piece 26 has released the latch, and for this purpose there is provided a spring device consisting of an arm 27 pivoted on a shaft 28, one end of the shaft being supported in a bracket 29 carried by the housing 10, the other end of the shaft fitting within an aperture 30 in the end wall of the housing.

The sound-deadening material 13 is cut out or slotted adjacent the bracket 29 so as to permit the bracket to project therethrough. The arm 27 has an elongated slot 31 therein, which provides side members 32 and an end member 33. A roller 34 projects through the slot 31 and is carried on a shouldered screw 35 threaded into a boss 36 formed in the end wall of the cover 11. A flat-headed screw 37 retains the roller 34 in position upon the shouldered screw 35 and sufficient clearance is allowed to permit free rotation of the roller. A pair of springs 38 and 38' are oppositely disposed within the slot 31 of the arm 27, one end of each spring being curved inwardly toward the opposite spring, and the other end of each spring fastened within the side members 32 of the slot by means of suitable bolts 39. The free ends of the springs 38 and 38' are bent parallel with the main body portion of the springs, and forked as indicated at 40. The forked ends of the springs 38 and 38' extend from the slot on both sides thereof and partially around the end member 33 of the

arm 27 to provide guide means for the free ends of the springs.

A worm-wheel 41 is mounted upon the shaft 28, and includes a hub portion 42 projecting through a perforation 42' in the pivoted end of the arm 27, and provides a bearing upon which the arm may be moved angularly. In bracket 29 is threaded a set-screw 44, the end of the screw tightening against a flat place 44' on the shaft 28 to secure the same against rotation. A worm 45 meshing with the worm-wheel 41 is mounted in trunnions, which may be formed on the arm 27, as shown at 47. It will be noted that the worm is retained within the trunnions by the worm-wheel 41, and is provided with a slot 48, so as to enable the worm to be turned by means of a screw-driver in adjusting the device.

A heavy coil spring 49 encircles the shaft 28, one end 50 of the spring fitting into a perforation in the worm-wheel 41, the other end 51 of the spring engaging under the bracket 29, the action of the spring being to raise the cover when the cover is released by the latch 23. A washer 52 may be provided between the arm 27 and the end wall of the housing 10. It will be readily understood that when the worm 45 is turned, the worm-wheel 41 winds up the spring 49 and by this means a very fine adjustment may be made to position the spring to the exact amount necessary to prevent opening the cover too violently. During the time that the cover is being opened by the tension of the spring 49, the roller 34 bears directly against the spring 38 causing the roller to revolve, thus providing a smooth and practically frictionless connection between the arm 27 and the cover 11.

It will be noted that the distance between the center of the hinge 12 and the roller 34 is greater than the distance from the pivotal point of the arm 27 and said roller. It will also be noted that the pivotal point of the arm 27 is somewhat below the line drawn through the center of the hinge 12 and the roller 34, so that when the arm 27 is actuated to move the cover, the screw 35 carrying the roller 34 moves in the slot 31 toward the free end of the arm until arrested by the curved portions of the springs 38 and 38', which cause the cover to be brought to rest in open position, due to the wedging action of the roller between the springs. During this operation, the cover has been smoothly moved from the position shown in Figure 1 and gradually brought to rest in the Figure 2 position without shock or vibration.

Variations may be resorted to within the scope of the invention, and portions of the improvements may be used without others.

Having thus described my invention, I claim:

1. The combination with a sound-deaden-

ing casing for a typewriting machine including a body, a cover hinged thereto, and releasable means for holding the cover closed, of a cover-opening device including an arm pivoted to the body, a connection from the cover to the arm and moving with relation thereto when the cover is released to open, means for automatically swinging the arm around its pivot, and a pair of friction devices carried by the arm and effective to engage the connection for gradually arresting the movement of the cover as it swings to open position.

2. The combination with a sound-deadening casing for a typewriting machine including a body, a cover hinged thereto, and releasable means for holding the cover closed, of a cover-opening device including an arm pivoted to the body, a connection from the cover to the arm and moving with relation thereto when the cover is released to open, means for automatically swinging the arm around its pivot, and a pair of oppositely-disposed spring members secured to the arm and receiving the connection in slidably relation thereto, said spring members being curved inwardly toward one another to provide a wedging action upon said connection to gradually arrest the movement of the cover when thrown open by the action of the arm.

3. The combination with a sound-deadening casing for a typewriting machine including a body, a cover hinged thereto, and releasable means for holding the cover closed, of a cover-opening device including an arm pivoted to the body and having a pin-and-slot connection with the cover, means for automatically swinging the arm around its pivot to open the cover when released, and means associated with said slot and effective to frictionally engage the pin to limit the throw of the arm when opening the cover.

4. The combination with a sound-deadening casing for a typewriting machine including a body, a cover hinged thereto, and releasable means for holding the cover closed, of a cover-opening device including an arm pivoted to the body and having a pin-and-slot connection with the cover, means for automatically swinging the arm around its pivot to open the cover when released, and means associated with said slot and effecting a wedging action against the pin to gradually arrest the movement of the cover when opening.

5. The combination with a sound-deadening casing for a typewriting machine including a body, a cover hinged thereto, and releasable means for holding the cover closed, of a cover-opening device including an arm pivoted to the body and having a pin-and-slot connection with the cover, means for automatically swinging the arm around its pivot to open the cover when released, and a

- pair of spring members secured within the slot on opposite sides of the pin, the free ends of said spring members being curved inwardly toward each other and effecting a 5 wedging action against the pin to gradually arrest movement of the cover when approaching open position.
6. The combination with a sound-deadening casing for a typewriting machine including a body, a cover hinged thereto, and releasable means for holding the cover closed, of a cover-opening device including an arm pivoted to the body, said arm having a slot therein, a roller carried by the cover 10 and moving in the slot, means for automatically swinging the arm around its pivot to open said cover when released, and means associated with said slot and effective to frictionally engage said roller to gradually 15 arrest the movement of the cover when opening.
7. The combination with a sound-deadening casing for a typewriting machine including a body, a cover hinged thereto, and releasable means for holding the cover closed, of a cover-opening device including an arm pivoted to the body, said arm having a slot therein, a roller carried by the cover 20 and moving in the slot, means for automatically swinging the arm around its pivot to open said cover when released, and means associated with said slot to permit the roller to have free rotational movement thereon 25 during a portion of the opening of the cover and then to frictionally engage said roller to gradually arrest the movement of the cover as the same approaches open position.
8. The combination with a sound-deadening casing for a typewriting machine including a body, a cover hinged thereto, and releasable means for holding the cover closed, of a cover-opening device including an arm pivoted to the body, said arm having 30 a slot therein, a roller carried by the cover and moving in the slot, means for automatically swinging the arm around its pivot to open said cover when released, and a pair of oppositely-disposed spring members secured within the slot and engaging the roller, the free ends of said spring members being curved inwardly toward each other and effecting a wedging action to cause the roller to gradually arrest the 35 movement of the cover as it approaches open position.
9. The combination with a sound-deadening casing for a typewriting machine including a body, a cover hinged thereto, and releasable means for holding the cover closed, of a cover-opening device including an arm pivoted to the body, a connection from the cover to the arm and moving with 40 relation thereto when the cover is released to open, means for automatically swinging the cover, means for holding the cover closed around its pivot, and a pair of oppositely-disposed spring members secured to the arm and receiving the connection in 45 sliding relation therewith, said members being curved inwardly toward one another so as to cause said connection to force the members apart to increase the frictional engagement between said connection and members and thereby gradually arrest movement of the cover as the same approaches 50 open position.
10. The combination with a sound-deadening casing for a typewriting machine having a body, a cover hinged thereto, and releasable means for holding the cover closed, of a cover-opening device including an arm pivoted to the body and having a connection to the cover, resilient means for turning said arm around its pivot to open the cover when released, and a worm-and-wheel connection between the arm and the resilient means for varying the tension of 55 said resilient means to regulate the throw of the arm.
11. The combination with a sound-deadening casing for a typewriting machine having a body, a cover hinged thereto, and releasable means for holding the cover closed, of a cover-opening device including a shaft mounted in the body, an arm swingable around said shaft, a connection between the arm and the cover, a worm-wheel secured to the shaft and movable angularly with relation to the arm, a worm carried by the arm and meshing with said worm-wheel, and a coiled spring disposed around the shaft for opening the cover when released, one end of the spring engaging the body and the other end carried in the worm-wheel, so that, upon turning the worm, the 60 tension of said spring may be varied and the cover-opening effort of the arm regulated.
12. The combination with a sound-deadening casing for a typewriting machine including a body, a cover hinged thereto, and releasable means for holding the cover closed, of a cover-opening device including an arm pivoted to the body, a connection from the cover to the arm and moving with 65 relation thereto when the cover is released to open, resilient means for automatically swinging said arm around its pivot to impart motion to the cover, means associated with said arm and connection for gradually 70 arresting and then stopping the movement of the cover as the same nears its open position, and a worm-and-wheel connection between the arm and the resilient means for varying the tension of said resilient means to regulate the throw of the arm.
13. The combination with a sound-deadening casing for a typewriting machine having a body, a cover hinged thereto, and releasable means for holding the cover 75 closed around its pivot, and a pair of oppositely-disposed spring members secured to the arm and receiving the connection in sliding relation therewith, said members being curved inwardly toward one another so as to cause said connection to force the members apart to increase the frictional engagement between said connection and members and thereby gradually arrest movement of the cover as the same approaches 80 open position.

closed, of a cover-opening device including an arm pivoted to the body and having a pin-and-slot connection with the cover, resilient means for causing a throw of the 5 arm so as to impart movement to the cover, a worm-and-wheel connection between the arm and the resilient means for varying the tension of said resilient means, and means associated with the slot and effective to cause an increasing frictional action against 10 the pin to gradually arrest and then stop the movement of said cover as it approaches open position.

JOSEPH LINDBURG.
